PUMP ACTUATING MECHANISM FOR RAIL LUBRICATORS

Sidney E. Bates, Chicago, Thomas E. Rodman, Glencoe, and Emmons Overmier, La Grange, Ill., assignors, by mesne assignments, to Poor & Company, Chicago, Ill., a corporation of Delaware

Application February 21, 1938, Serial No. 191,602

15 Claims.

(Cl. 184—3)

This invention relates to certain new and useful improvements in pump actuating mechanism for rail and wheel flange lubricators and more particularly to pump actuating mechanism including a reciprocating plunger supported on a rail at one side thereof and adapted to be operated by contact with passing car wheels.

Wheel engaging plungers in the form of reciprocating studs have been used heretofore in rail and wheel flange lubricators as valve members and as direct acting lubricant pumps, but they have been regarded as wholly unsuitable for imparting operating movement to lubricant pumps located at substantial distances from the rail.

15 The sudden impact, when a car wheel strikes such plunger and the consequent high velocity movement imparted to it and the shaft connections from a position of rest imposes severe strains on the pump mechanism and the operating connections. It has been customary, heretofore, to operate such pump mechanism by means of relatively long wheel engaging levers arranged along one side of the rail or by other speed reducing lever connections interposed between a wheel engaging element and the pump.

An object of the present invention is to provide, in a rail and wheel flange lubricating apparatus, compact and relatively inexpensive pump actuating mechanism including a wheel engaging plunger for imparting movement to a pump shaft, the mechanism being such as to prevent undue strains being imposed on the pump or other operative connections by the sudden impact or starting movement of the plunger when it is struck by a car wheel.

According to the invention, the pump operating mechanism includes a shaft extending from the location of the pump to the rail and is connected to a plunger adapted to be depressed by engagement with a wheel passing along a rail. The plunger is so constructed and connected to the shaft as to avoid the strains ordinarily imposed on a shaft and pump structure when a wheel actuating plunger is connected directly to the shaft. In one embodiment of the invention, the shaft is operated by means of spring pressure during the return or upward movement of the plunger. In another embodiment, the pump is operated during a downward movement of the plunger by a resilient cushion, preferably a compression spring, interposed in the plunger so as to absorb the shock incident to the impact of the wheel against the upper end of the plunger, the operating force being thereby exerted on the

shaft through the said compression spring cushion.

Another more specific object of the invention is to provide improved ratchet means for effecting operative connection between a vertically operated plunger member and the operating shaft of a lubricant pump, whereby a relatively short movement of the plunger may be fully translated into an operating movement of the shaft. In this connection the invention provides means for adjusting the actuating detent and/or the holding detent so that both of these members will be fully engaged with the ratchet wheel.

Other objects and advantages of the invention will be readily apparent from the following detail descriptions of the two embodiments illustrated in the drawings.

In the drawings:

Fig. 1 is a plan view of a rail and wheel flange lubricating apparatus provided with a pump actuating mechanism made in accordance with this invention.

Fig. 2 is a side view, on a larger scale than Fig. 1, illustrating the manner in which the pump shaft actuating mechanism is adjustably secured on the rail.

Fig. 3 is a vertical sectional view taken through the lubricant reservoir and part of the pump actuating mechanism.

Fig. 4 is a view in perspective of a ratchet mechanism employed in the shaft operating mechanism illustrated in Fig. 3.

Fig. 5 is a sectional view taken through the rail substantially on line 5—5 of Fig. 1 and looking in the direction indicated by the arrow.

Fig. 6 is an end view of the mechanism shown in Fig. 5 with the end cover of the casing removed and with a portion of the cover engaging flange broken away.

Fig. 7 is a fragmentary sectional view taken on line 7—7 of Fig. 6 to illustrate the eccentric bolt for varying the position of the actuating detent.

Fig. 8 is a view similar to Fig. 3 but illustrating a reciprocating pump and a wheel actuated mechanism which is particularly suitable for such form of pump.

Fig. 9 is a sectional view on line 9—9 of Fig. 8 with part of the clamp omitted.

Fig. 10 is a cross section taken through the lubricant distributor, the rail, and the wheel actuated plunger mechanism, the said section being taken on line 10—10 of Fig. 9, and

Fig. 11 is a sectional plan view taken on line 11—11 of Fig. 9.

Referring first to Figs. 1 to 7 inclusive of the

drawings: 10 designates a lubricant supply reservoir adapted to be embedded in the road-bed at one side of the rail 11. A suitable pump mechanism 12, preferably a rotary type, is located adjacent the supply reservoir so as to withdraw lubricant therefrom and force it through conduits 13—13 to one or more lubricant distributors 14 secured to the rail. The said distributors may be of any suitable construction adapted to discharge lubricant at one side of a rail head so that the lubricant will be spread along the side face of the rail head and/or picked up by the flanges of car wheels passing along the rail.

Inasmuch as the distributing members and the reservoir structure is shown herein merely to illustrate a complete operative structure and do not in themselves constitute a material part of the present invention these members of the lubricating apparatus will not be described in detail. Any further detail of operation may be had by reference to the Bates and Overmier Patent No. 2,055,140 dated September 22, 1936.

The pump 12 is operated by means of sprocket and chain connections 15 with a flexible shaft designated as a whole by the reference numeral 16. The said shaft 16 is made flexible so that it will automatically adjust itself to compensate for movements of the rail relative to the pump, during the passing of traffic over the rail. The end section 17 of the flexible shaft extends into a casing 18 which encloses mechanism, including a wheel actuated plunger 19, for imparting operating movements to the shaft.

The mechanism casing 18 is preferably adjustably secured to a supporting bar 20 at the outer side of the rail by means of angular brackets 21—21 (Fig. 2) there being slots 21^a in the angle brackets for the fastening bolts 22; the supporting bar 20 is adjustably supported near its ends on clamp brackets 23—23 and is supported intermediate its ends by adjusting screws 23^a which bear on the top surface of the rail base flange. The plunger 19 is preferably cylindrical and is supported in the casing 18 in a position inclined transversely of the rail (Figs. 3 and 5). By positioning the plunger in the inclined position, the length of the plunger may be made substantially greater than the height of the rail and the upper end of the plunger may be positioned relatively close to the outer side face of the rail head for contact with the tread portion of a wheel. The diameter of the upper portion 24 of the plunger is preferably less than the body portion and extends through a suitable bearing 25 in the casing. The shoulder 26 at the lower end of the reduced portion of the plunger serves as a stop to limit the upward movement of the plunger. The plunger is supported in its normal position by means of a coil spring 27. The upper portion of the spring extends into a cylindrical pocket formed in the lower end of the plunger and the lower end of the spring seat on a removable plug 28. The plunger is operatively connected, as hereinafter described, to the end sections 17 of the flexible shaft, the latter being journaled in bearings 29 and 30 in the removable closure head 31 and the rear wall, respectively, of the casing 18.

The mechanism for connecting the plunger 19 with the flexible shaft comprises a ratchet wheel 32 fixed to the section 17 of the shaft and an oscillating lever means mounted loosely on the shaft adjacent to said ratchet wheel. The lever means comprises a hub portion 33 (Fig. 4) formed at one side with a projection 34 adapted

to extend into a horizontal slot 35 formed in the plunger. The upper and lower faces of the projection 34 are preferably curved so as to bear against the walls of the slot 35 during all angular positions of the lever. At the other side of the said hub portion 33 it is provided with two radially projecting arms 36 and 37. An actuating detent 38 is pivotally supported on a bolt 39 fixed adjustably in the outer end of the arm 36. The actuating detent normally hangs downwardly and is provided at its lower end with a plurality of teeth 40 adapted to engage the teeth of the ratchet wheel. A spring 41 positioned in a spring pocket 42 on the arm 37 bears against the outer face of the detent 38 so as to hold it in engagement with the ratchet wheel at all times. A holding detent 43 is pivotally supported on a bolt 44 which screws into a lug 45 projecting inwardly from the inner wall of the casing 18. The free end of the holding detent is provided with a plurality of teeth 46 adapted to engage the teeth of the ratchet wheel 32. The tooth end portion of the holding pawl is held in engagement with the ratchet wheel by means of a coil spring 47 positioned in a spring pocket in the lower portion of the casing 18. The compression of the spring 46 may be adjusted by turning a plug 48 which serves as a closure for the spring pocket.

In order to insure proper engagement of the detent 38 with the teeth of the ratchet wheel and thereby avoid any substantial lost motion at the beginning of the downward movement of said detent, and in order also to insure proper engagement of the holding detent 43 with the teeth of the ratchet wheel at the end of each operative movement of the wheel, one or both of the detents may be adjusted to shift the pivotal axis thereof. The means for adjusting the detent 38 comprises an eccentric portion 49 formed on the pivot bolt 39. It will be seen by inspection of Figs. 6 and 7 that rotation of the pivot bolt 39 in a counterclockwise direction moves the eccentric portion of the bolt in a direction to elevate the detent 38 relative to the ratchet wheel 45 and that rotation of said pivot bolt in the other direction lowers the detent relative to the ratchet wheel. The means for adjusting the detent 43 comprise an eccentric bushing 43^a fixed in an opening at the pivot end of the detent and a set screw 43^b for holding the eccentric bushing in any desired position of adjustment. Rotation of the bushing in the holding detent in a counterclockwise direction, as viewed in Fig. 6, serves to increase the effective length of the detent. Rotation of the said bushing 43^a in the other direction serves to shorten the effective length of the detent. In this way the detent 43 can be accurately positioned to engage one or more teeth of the ratchet wheel at the end of each partial rotation thereof.

In order to insure thorough lubrication of the parts, the casing is partially filled with a suitable lubricant before the closure head 31 of the casing is applied. A removable plug 50 in the head 31 (Fig. 2) permits ready inspection of the lubricant and the introduction of additional quantities thereof from time to time.

In operation, the portion of a wheel tread which overlies the outer side face of a running rail engages the upper end of the plunger 19 so as to depress this member. During the downward movement of the plunger the ratchet lever means is rocked in a direction to elevate the actuating detent 38. As soon as the car wheel 75

passes off the plunger the compression spring 27 forces the plunger upwardly. During the upward movement of the plunger the pressure of spring 27, acting through the ratchet mechanism, 5 effects a partial rotation of the flexible shaft 16. This partial rotation of the shaft imparts a pumping movement to the pump 12 by means of the chain and sprocket connection 15. The lubricant withdrawn from the reservoir 10 is forced 10 by the pump through the conduits 13-13 to the distributors 14-14, the latter members serving to discharge the lubricant at locations where it is brought into contact with the inner face of the rail head and the flanges of passing car 15 wheels.

Referring now to the modified embodiment illustrated in Figs. 8 to 11 inclusive, of the drawings: 51 designates, as a whole, a plunger mechanism secured in a casing 52, the latter of which 20 is adjustably supported on a supporting bar 20^b by means of bolts 53 extending through elongated slots 54. The said supporting bar 20^b is provided at its ends with adjusting screws 20^c whereby the bar may be raised or lowered relative to the rail. The bar is adjustably clamped to the rail by means of the same clamp structure illustrated in the previous embodiment, comprising the clamp 23, a clamp jaw 73 and a connecting bolt 74. The said plunger 51 comprises an 25 outer cylindrical member 55 and an inner member 56, the inner member is connected to the outer member by means of a pin 57 which extends through an opening 58 in the inner member. The said opening 58 is somewhat larger 30 than the pin 57 so that the inner and outer members of the plunger may move relative to each other when a car wheel strikes the upper end of the plunger. This relative movement is resisted by a compression spring 59 interposed 35 between the outer and inner members of the plunger. The said spring absorbs the initial shock accompanying the impact of the car wheel against the plunger and converts this force into resilient pressure which is transmitted through 40 a lever 60 to the flexible shaft 61. The said relative movement of the plunger members is, preferably, limited by the shoulder 62 which engages the upper edge of the inner member 56 when the spring 59 is substantially fully compressed. 45 A screw bolt 63 (Fig. 10) extends through the casing and projects into a slot 64 in the outer member of the plunger to hold the plunger against rotary movement. This bolt serves also 50 as a stop to limit upward movement of the plunger in the casing. The outer end of the lever 60 extends into a slot 65 formed in the lower end of the outer member of the plunger. Preferably, this end of the lever is curved and extends upwardly as indicated at 60^a so as to permit a relatively close arrangement of the plunger and the shaft 61 and at the same time insure contact of the lever at substantially the center of the plunger inner member 56 during all angular positions of the lever. The outer end of the flexible shaft 61 extends into the pump casing and is provided with a lever arm 66 which bears on the upper end of a reciprocating pump member 67 mounted in a casing 68 on a lubricant supply reservoir 69. A compression spring 70 surrounding 65 a portion of the pump piston 67 holds the pump in its normal up position and thereby holds the plunger 51 in its up position and in the path of travel of a car wheel.

70 In operation, a car wheel passing along the

75 rail 11^a engages and depresses the plunger 51. The initial impact of the wheel against the plunger is absorbed by the compression spring 59 so as to relieve the lever 60 and the other pump operating mechanism from the shock of 10 said impact. Downward movement of the plunger 51 imparts a rocking movement to the lever 60 and to the shaft 61. This movement of the shaft rocks the lever arm 66 downwardly and forces the pump 67 downwardly. The downward movement of the pump compresses the spring 70 and also forces lubricant past a ball valve 71 and thence through the conduits 13^a to the lubricant distributor 14^a. As soon as the car wheel passes over the plunger 51 the reaction of the compression spring 70 returns all of the operating parts to the positions shown in Figs. 8 to 11, inclusive, of the drawings so that the parts will be in readiness for another pumping operation.

15 The discharge means 14^a shown in this modification may be and preferably is of the same general construction as illustrated in Fig. 3. It is supported on the rail by means of a vertically adjustable bar 72 and pedestal clamp members 73.

20 While the invention is illustrated in connection with two specific embodiments it will be obvious that various changes in specific construction may be made without departure from the principles of the invention disclosed. It should be understood, therefore, that the invention is not to be limited to the structure shown and described except insofar as they appear in, the appended claims.

25 We claim:

30 1. In a rail and wheel flange lubricating apparatus, the combination with means for delivering lubricant to the rail comprising a pump and operating connections therefor including a shaft; of means for imparting movement to said shaft comprising a stud plunger movable in the direction of its length and supported on the rail at one side thereof in relatively close relation to the said shaft and with its upper end extending into the path of passing car wheels, whereby the plunger is depressed by engagement with said 35 wheels, lever means on said shaft including a relatively short arm for engaging the plunger, whereby movement of the plunger in one direction imparts a partial rotation to said shaft, and a spring associated with the plunger for imparting 40 resilient operating pressure on the lever.

45 2. In a rail and wheel flange lubricating apparatus, the combination with means for delivering lubricant to the rail comprising a pump and operating connections therefor including a shaft; of means for imparting movement to said shaft comprising a stud plunger movable in the direction of its length and supported on the rail at one side thereof, in close relation to the shaft, a 50 spring for supporting the plunger in its up position, in which position its upper end extends into the path of travel of car wheels passing along the rail, lever means on said shaft for engaging the plunger, whereby movement of the 55 plunger in one direction imparts a partial rotation to said shaft, and resilient means interposed between the wheel engaging end of the plunger and the lever for cushioning the initial operating force on the lever.

60 3. In a rail and wheel flange lubricating apparatus, the combination with means for delivering lubricant to the rail comprising a pump and operating connections therefor including a shaft; of means for imparting movement to said shaft 65

- comprising a casing mounted on the rail at one side thereof, a vertically movable stud plunger supported in the casing in close relation to the shaft with its upper end extending through the top of the casing and into the path of travel of car wheels passing along the rail, whereby the plunger is depressed by engagement with said wheels, lever means including a relatively short arm on said shaft within said casing and engaging the plunger so that movement of the plunger in one direction imparts a partial rotation to said shaft, and a spring associated with the plunger for applying resilient operating pressure on the shaft.
4. In a rail and wheel flange lubricating apparatus, the combination with means for delivering lubricant to the rail comprising a pump and operating means therefor including a shaft; of means for imparting movement to said shaft comprising a casing mounted on the rail at one side thereof, a vertically movable stud plunger supported in the casing in close relation to the said shaft and with its upper end extending into the path of passing car wheels, there being a transverse recess in the plunger, a lever means mounted on the shaft and including a relatively short arm extending into the said recess in the plunger for operatively engaging the plunger at a location intermediate its ends, whereby movement of the plunger in one direction imparts a partial rotation to said shaft, and a spring associated with the plunger for applying resilient operating pressure on the lever.
5. In a rail and wheel flange lubricating apparatus, the combination with means for delivering lubricant to the rail comprising a pump and operating means therefor including a shaft, of means for imparting intermittent movements to the shaft in one direction comprising a closed casing for one end of the shaft adapted to contain a quantity of lubricant, a plunger mounted to reciprocate vertically in the casing and having a transverse slot therein, a spring for holding the plunger yieldably in the path of passing car wheels, and means for connecting the plunger with the shaft comprising a member loosely mounted on the shaft so as to oscillate thereon and having a portion in the form of a gear tooth extending into the slot formed in the plunger, a ratchet wheel on the shaft, an actuating detent arm pivotally supported on the oscillating member for engaging the teeth of the ratchet wheel, and a holding detent for preventing reverse movement of the ratchet wheel; the actuating detent and the gear tooth portion of the oscillating member being arranged on opposite sides of the shaft, whereby the shaft is rotated by the force of the plunger spring during the upward movement of the plunger.
6. In a rail and wheel flange lubricating apparatus including a pump and operating means therefor comprising a shaft; wheel actuated mechanism for operating the shaft comprising a reciprocating plunger supported on the rail, a spring for normally holding the plunger in the path of travel of a car wheel, whereby the plunger is operated by engagement with said wheel, a ratchet wheel fixed on the shaft, a lever means oscillatably supported on the shaft and connected to the plunger, an actuating detent pivotally supported on the lever means and having teeth for engaging the ratchet, whereby movement of the plunger in one direction imparts a partial rotation to the ratchet, a spring for holding the actuating detent in engagement with the ratchet, a pivoted holding detent having teeth for engaging the teeth of the ratchet wheel to prevent reverse movement; the pivotal axis for one of

actuating detent in engagement with the ratchet, a pivoted holding detent having teeth engaging the teeth of the ratchet wheel to prevent reverse movement, and means for adjusting one of said detents relative to the ratchet wheel, whereby the said actuating and holding detents will engage the vertical faces of the ratchet wheel teeth when the movable parts of the actuating mechanism are at rest.

7. In a rail and wheel flange lubricating apparatus including a pump and operating means therefor comprising a shaft; wheel actuated mechanism for operating the shaft comprising a reciprocating plunger supported on the rail, a spring for normally holding the plunger in the path of the car wheels, whereby the plunger is operated by engagement with said wheel, a ratchet wheel fixed on the shaft, a lever means oscillatably supported on the shaft and connected to the plunger, an actuating detent arm pivotally supported on the lever means and having teeth for engaging the ratchet, whereby movement of the plunger in one direction imparts partial rotation to the ratchet, a spring for holding the actuating detent in engagement with the ratchet, a pivoted detent arm having teeth engaging the teeth of the ratchet wheel to prevent reverse movement, and an eccentric member providing a pivotal axis for one of said detent arms, whereby the position of the detent may be adjusted relative to the ratchet wheel by rotation of the eccentric member.

8. In a rail and wheel flange lubricating apparatus including a pump and operating means therefor comprising a shaft; wheel actuated mechanism for operating the shaft comprising a reciprocating plunger supported on the rail, a spring for normally holding the plunger in the path of the car wheels, whereby the plunger is operated by engagement with said wheels, a ratchet wheel fixed on the shaft, a lever means oscillatably supported on the shaft and connected to the plunger, an actuating detent pivotally supported on the lever means and having teeth for engaging the ratchet, whereby movement of the plunger in one direction imparts a partial rotation to the ratchet, a spring for holding the actuating detent in engagement with the ratchet, a pivoted holding detent having teeth for engaging the teeth of the ratchet wheel to prevent reverse movement, the pivotal axis for one of said detents comprising a bolt formed with an eccentric portion, whereby rotation of the bolt alters the position of the detent arm relative to the other arm.

9. In a rail and wheel flange lubricating apparatus including a pump and operating means therefor comprising a shaft; wheel actuated mechanism for operating the shaft comprising a reciprocating plunger supported on the rail, a spring for normally holding the plunger in the path of the car wheels, whereby the plunger is operated by engagement with said wheels, a ratchet wheel fixed on the shaft, a lever means oscillatably supported on the shaft and connected to the plunger, an actuating detent pivotally supported on the lever means and having teeth for engaging the ratchet, whereby movement of the plunger in one direction imparts a partial rotation to the ratchet, a spring for holding the actuating detent in engagement with the ratchet, a pivoted holding detent having teeth for engaging the teeth of the ratchet wheel to prevent reverse movement; the pivotal axis for one of

5 said detents comprising an eccentric bushing revolvably positioned in an opening in the pivotal end of the detent, whereby rotation of the eccentric bushing relative to the detent varies the effective length of the detent.

10. In a rail and wheel flange lubricating apparatus, the combination of means for delivering lubricant to the rail comprising a pump and operating means therefor including a shaft, of means for imparting movement to said shaft comprising a casing mounted on the rail at one side thereof, a plunger supported in the casing to move in a plane inclined to the vertical center plane of the rail, there being a transverse recess 15 in the plunger which is in normal alignment with the axis of the pump operating shaft, and a lever means mounted on the shaft and extending into said recess in the plunger for operatively connecting the plunger with said shaft, whereby movement of the plunger in one direction imparts a partial rotation to said shaft.

11. In a rail and wheel flange lubricating apparatus, the combination with means for delivering lubricant to the rail comprising a pump and operating means therefor including a shaft; of means for imparting movement to said shaft comprising a casing mounted on the rail at one side thereof, a plunger supported in the casing to move in a plane inclined to the vertical with the upper end of the plunger extending into the path of travel of car wheels passing along the rail, there being a transverse recess in the plunger and extending in a horizontal plane, and a lever means mounted on the shaft and extending into said recess in the plunger for operatively connecting the plunger with said shaft, whereby movement of the plunger in one direction imparts a partial rotation to said shaft.

12. In a rail and wheel flange lubricating apparatus the combination with means for delivering lubricant to a rail comprising a pump and operating connections therefor including a shaft; of means for imparting movement to said shaft comprising a stud plunger positioned in close relation to said shaft at a location adjacent the outer side face of a rail head for engagement with the tread portions of passing car wheels, means for adjustably supporting the plunger on the rail so as to accommodate rails of different heights, lever means on said shaft including a relatively short arm for engaging the plunger, whereby movement of the plunger in one direction imparts a partial rotation to said shaft, and means associated with the plunger for applying resilient operating pressure on the lever.

13. In a rail and wheel flange lubricating apparatus including a pump and operating mechanism therefor comprising a shaft; wheel actuated mechanism for operating the shaft comprising a lever fixed on the shaft and a vertically operating plunger engaging the outer end of the lever and positioned to be depressed by a

passing car wheel, whereby the downward movement of the lever imparts a partial rotation to the shaft; the said plunger comprising an outer member, an inner member which bears on the lever and has a transverse opening therethrough, 5 a connecting pin extending loosely through said opening and engaging the outer member for connecting the outer and inner members together with capacity for relative movement, and a compression spring interposed between the inner and outer members to provide a shock absorbing cushion.

14. In a rail and wheel flange lubricating apparatus including a pump and operating mechanism therefor comprising a shaft; wheel actuated mechanism for operating the shaft comprising a lever fixed on the shaft and having a rounded upwardly projecting end, and a vertically operating plunger engaging the said rounded end of the lever and positioned to be depressed by a 20 passing car wheel whereby the downward movement of the lever imparts a partial rotation to said shaft; the said plunger comprising outer and inner members having telescopic relation, a connecting pin extending loosely through a 25 transverse opening in the inner member to hold said inner and outer members in their assembled relation with capacity for relative movement, a compression spring interposed between the outer and inner members to provide a cushion 30 to resist inward endwise movement of said members, and stop means positioned to limit upward movement of the plunger structure.

15. In a rail and wheel flange lubricating apparatus including a pump and operating mechanism therefor, comprising a shaft; wheel actuated mechanism for operating the shaft comprising a lever fixed on the shaft and a vertically operating plunger engaging the outer end of the lever and positioned to be depressed by passing 40 car wheels, whereby the downward movement of the lever imparts a partial rotation to the shaft; the said plunger comprising outer and inner hollow members having telescopic relation with each other, a connecting pin carried by said 45 outer member and extending loosely through a transverse opening in the inner member to hold said members in their assembled relation with capacity for relative movement, a compression spring seated in the hollow portions of said 50 members to provide a cushion to resist relative inward movement of the members, and stop means for limiting the inward endwise movement of said hollow members comprising a shoulder 55 formed on the inner wall of the outer member adapted to engage the upper end of the said inner member when the spring is under maximum compression.
